STEREOSCOPIC CAMERA OR THE LIKE

Peter Schmuck, Vaduz, Liechtenstein, assignor to
Kamerabau-Anstalt, Vaduz, Liechtenstein

Application August 25, 1955, Serial No. 37,668

Term of patent 14 years

(Cl. D61—1)

Fig. 5

Fig. 1

Fig. 3

Fig. 4

Fig. 2

Fig. 1 is a front view of a stereoscopic camera or the like, showing my new design;

Fig. 2 is an inverted rear view of the camera;

Fig. 3 is a side view of the same;

Fig. 4 is a top view; and

Fig. 5 is a bottom view thereof.

I claim:

The ornamental design for a stereoscopic camera or the like, as shown.
